UNITED STATES PATENT OFFICE.

CLAUDE A. DUNN, OF DENVER, COLORADO.

DESIGN FOR A SPROCKET-WHEEL.

SPECIFICATION forming part of Design No. 29,142, dated August 2, 1898.

Application filed July 1, 1897. Serial No. 643,160. Term of patent 7 years.

To all whom it may concern:

Be it known that I, CLAUDE A. DUNN, a citizen of the United States of America, residing at Denver, in the county of Arapahoe and State of Colorado, have invented a certain new and original Design for Sprocket-Wheels for Bicycles; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My newly-designed sprocket-wheel is intended for use on bicycles, and has for its object the production of a sprocket-wheel which shall be ornamental in appearance and symmetrical in form.

20 Figure 1 is a side elevation of a sprocket showing my new design. Fig. 2 is a plan view of Fig. 1. Fig. 3 is a sectional view of Fig. 1 on line A.

The sprocket-wheel contains at its center a 25 hub member U, through which is formed an axial perforation V. From this hub socket portions S' project from the body portion of the hub R', and from the socket portions of the hub at and adjacent to the points T spokes 30 S project to a rim or felly B. The felly B comprises a circumferential rim which is joined to the spokes and is formed with two independent circumferential rows of projections C, which are provided with a broad base D. These projections C are separated from one another by a 35 deep recess or channel K, which extends circumferentially around the felly between them and completely isolates and separates them from one another. The projections of each row 40 are arranged opposite one another, and each projection of each row of projections is separated from its adjacent projection by a deep 45 semicircular concaved curve M, which extends to the lower edge of the felly and converges or bevels toward the center of the periphery of the channel K and dips at an oblique angle N to the opposite edges of the felly and rounds over into their peripheries at the corners L. Between each two projec-

tions of each row the felly swells from each side edge of the felly transversely across its periphery by a convex curve, and thus a transverse convex-shaped periphery is formed at these points on the felly at P between the projections and between the separated rows of 55 projections. Each projection contains two contiguous projecting teeth E and F, which are separated by a recess G, the bottom of which is slightly concaved, like the bottom of the letter U, from which point the members 60 curve outward and terminate with a semicircular curve that blends into round corners L and with it forms a round-topped tooth. These projecting teeth radiate from the opposite edges of each projection of each row that projects from the felly. From the center portion of the interior periphery of the felly a member Q depends between the spokes. This member extends circumferentially around the felly between the spokes and blends into the 70 felly by lateral curves R.

The essential feature of my design is a sprocket-wheel consisting of a concentrically-supported hub and a felly formed with two independent circumferential rows of radially-arranged independent projections on the extreme outside edges of the rim of the felly and arranged transversely opposite each other, with a deep wide channel between them which extends circumferentially around the felly, 80 and each row containing a broad semicircular concaved recess between each projection of each row and arranged with each independent projection of each row having two radially-projecting contiguous members formed 85 in its periphery at a short distance above the bottom of the channel between the projections and the beveled surfaces of the periphery of the felly between the projections.

I claim—

The design for a sprocket-wheel, substantially as herein shown and described.

In testimony whereof I affix my signature in presence of two witnesses.

CLAUDE A. DUNN.

Witnesses:

JOHN F. SANDERS,
JOSIAH A. FOWLER.
